UNITED STATES PATENT OFFICE.

CHARLES C. PRIMUS, OF EWING, NEBRASKA.

WAGON-POLE EXTENSION.

Application filed June 29, 1921. Serial No. 481,357.

To all whom it may concern:

Be it known that I, CHARLES C. PRIMUS, a citizen of the United States, residing at Ewing, in the county of Holt and State of Nebraska, have invented certain new and useful Improvements in Wagon-Pole Extensions; and I do hereby declare the following to be a full, clear, and exact description of the invention, such as will enable others skilled in the art to which it appertains to make and use the same.

Vehicles and analogous devices provided with draft poles or tongues and adapted to be drawn by horses frequently require the pole or tongue to be lengthened, particularly when doubling the team and arranging the animals four abreast.

The present invention provides an extension which not only may be readily applied to the pole or tongue to increase the length thereof when required but which may be adjusted to vary the effective length of the pole as best adapted to the particular need.

Other objects and advantages will be apparent and suggest themselves as the nature of the invention is understood.

While the drawing illustrates an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a side view of the forward end of a pole or tongue provided with an extension embodying the invention.

Figure 2 is a perspective view of the invention detached from the pole.

Figure 3 is a section on the line $x-x$ of Figure 1, and

Figure 4 is a section on the line $y-y$ of Figure 1.

Corresponding and like parts are referred to in the following description and designated in the several views of the drawing by like reference characters.

A pole or tongue 1 may be of any construction such as usually provided for vehicles and analogous devices adapted to be drawn by horse power. The pole 1 is provided at its outer or forward end with the usual metal disk 2 for cooperation with the neck yoke in a manner well understood.

The invention comprises a stub pole or

block 3 having a neck yoke stop 4 of any preferred construction. Metal straps 5 are secured at their forward ends to opposite sides of the stub pole 3 and extend in parallel relation and are connected at their rear ends by means of a clip 6 and bolt 7. The straps 5 are provided near their forward ends with a plurality of openings 8 which are in transverse alignment to receive a bolt 9 or like fastening. The bolt 9 is adapted to pass through the loops at the forward end of the pole 1 provided by means of the metal strip 2. The clip 6 is adapted to fit astraddle the pole 1 and is secured in the adjusted position by tightening the bolt or fastening 7. The straps 5 extend along opposite sides of the pole 1 and may be adjusted to bring any desired set of openings 8 in registering position with the loops at the forward end of the pole 1 whereby to receive the bolt or fastener 9. A strip 10 is mounted on the bolt 9 and is disposed to engage the bottom and opposite sides of the pole 1 whereby strengthening and reinforcing the straps 5 opposite the parts provided with the openings 8.

It will be readily understood from the foregoing taken in connection with the accompanying drawing that this invention provides an extension which may be readily applied to a vehicle pole or tongue and adjusted to vary the effective length thereof as required.

Having thus described the invention, what I claim is:

1. An extension for draft poles, the same comprising a stub pole having a neck yoke stop upon its under side, straps secured to the opposite sides of the stub pole and extending in approximately parallel relation, a clip at the rear ends of the straps, a bolt passing through registering openings formed in the overlapping ends of the clips and straps whereby to clamp the pole therebetween, a second clip engaging the outer sides of the lower edges of the straps near their forward ends, and a bolt connecting the overlapping portions of said second clip and the straps and adapted to clamp the forward end of the pole therebetween.

2. An extension for draft poles, the same comprising a stub pole having a neck yoke stop upon its under side, straps secured to the opposite sides of the stub pole and extending in approximately parallel relation, a clip at the rear end of the straps, a bolt

passing through registering openings formed in the overlapping ends of the clip and straps whereby to clamp the pole therebetween, a second clip engaging the outer sides 5 and the lower edges of the straps near their forward ends, and a bolt connecting the overlapping portions of said second clip and the straps and adapted to clamp the forward end of the pole therebetween, said straps 10 having a plurality of openings in their

length in the rear of the said stub pole to receive the bolt associated with said forward clip whereby the extension may be adjusted to vary the effective length of the pole.

In testimony whereof I affix my signature 15 in presence of two witnesses.

CHARLES C. PRIMUS.

Witnesses:

LEONARD HALES,
